DENTAL PARTIAL PLATE HOLDER

Charles D. Kreps, Hazel Crest, Ill.

Application January 26, 1939, Serial No. 252,989

3 Claims. (Cl. 32—5)

This invention relates to a denture device or means whereby partial plates may be removably but securely secured to a live tooth and efficiently supported.

5 It is further aimed to provide a structure having a bar or the like disposable behind teeth and with a clamp means extending therefrom to coact with a live tooth.

The more specific objects and advantages will 10 become apparent from a consideration of the description following taken in connection with the accompanying drawing illustrating an operative embodiment.

In said drawing:

15 Figure 1 is a view in front elevation showing the improvement in use;

Figure 2 is a plan view of the improvement, a live tooth being shown in cross section;

20 Figure 3 is a vertical section taken on the line 3—3 of Figure 1;

Figure 4 is a plan view of the parts minus the teeth;

25 Figure 5 is a view in front elevation of the parts of Figure 4; and

Figure 6 is a fragmentary front elevation of a portion of the artificial tooth or teeth employed.

Referring specifically to the drawing wherein like reference characters designate like or similar parts, the improvements may be employed in 30 connection with either upper or lower teeth. A metallic bar 10 is provided of a width less than the height of the teeth, that is the natural teeth of the user, and the same is disposed behind the teeth, being arcuate or having a deflected portion 35 as at 11, enabling abutting contact of the bar with at least one live tooth of the user as at 12, it being understood, that the bar may abut any desired number of teeth. An artificial tooth member 13, is vulcanized to the bar 10 and this 40 member may represent a single tooth or any desired number of teeth, according to the removed natural teeth, such tooth member 13 preferably being concave as at 14 in its upper edge, to intimately fit and have suctional contact with the 45 gum.

Extending forwardly from the bar 10 is a stud 15 riveted or otherwise rigidly fastened to the bar as at 16. It will be noted that the artificial tooth member 13 has a notch 17 at one end which 50 receives the stud 15 and thus offers great support and reinforcement to the tooth member,

especially when biting. A bar or plate 18 of suitable size overlaps the artificial tooth member 13 and the natural tooth 12 and the structure is rigidly clamped to the natural tooth 12 by the bars 11 and 18, through the action of a screw 19 threaded through bar 18 and into the stud as at 20, said screw having its head 21 finished in any desired manner, countersunk, if desired, or otherwise.

It will be obvious, that where conditions warrant or it is desired, more than one of the plates 18 and associated parts may be used, according to the position of the natural teeth in the mouth of the patient and the artificial teeth to be used on the bar.

15 Various changes may be resorted to provided they fall within the spirit and scope of the invention.

I claim as my invention:

1. A dental device of the class described comprising a bar, a stud projecting forwardly from the bar, a plate spaced from the bar by said stud, screw means securing the plate to the bar, artificial tooth means clamped to the bar by one end portion of the plate under the action of the screw 25 means, the plate at the other end portion extending beyond the tooth means and adapted jointly with the bar and screw means to clamp against opposite faces of a tooth.

2. A dental device of the class described comprising a bar, a stud projecting forwardly from the bar, a plate shorter than the bar spaced from the bar by said stud, screw means securing the plate to the bar, artificial tooth means clamped to the bar by one end portion of the plate under 35 the action of the screw means, the plate at the other end portion extending beyond the tooth means and adapted jointly with the bar and screw means to clamp against opposite faces of a tooth, said artificial tooth means at one end having an open notch interfitting with the stud.

3. A dental device comprising a bar, a stud extending therefrom, artificial tooth means on the bar interfitting with the stud, a plate bearing against the free end of the stud projecting beyond one end of the tooth means to coact with the bar for clamp engagement with a natural tooth, and a securing screw extending through the plate and engaging said stud.

50

CHARLES D. KREPS.
